E. S. DANIELSON

SPRAY

Filed July 30, 1926

INVENTOR.

E. S. DANIELSON
BY *Victor J. Evans*
ATTORNEYS.

UNITED STATES PATENT OFFICE.

EDNA S. DANIELSON, OF BERKELEY, CALIFORNIA.

SPRAY.

Application filed July 30, 1926. Serial No. 126,029.

This invention relates to improvements in sprays, and has particular reference to a spray adapted to be used upon the body.

The principal object of this invention is to produce a spray having a guard attached thereto, which guard will prevent any unnecessary splashing of water issuing from the spray.

Another object is to produce a spray which is cheap to manufacture, simple in construction and therefore well within the purchase price of the average user.

A further object is to produce a device of this character which may be employed in any place where a spray is now employed.

Other objects and advantages will be apparent during the course of the following description.

In the accompanying drawings forming a part of this specification and in which like numerals are employed to designate like parts throughout the same,

Figure I is a side elevation of my improved spray, partly broken away so as to show the construction thereof, and

Figure II is a bottom plan view of my spray.

Sprays as ordinarily employed, consist of a rubber top having a spray head which the operator grasps and directs the water issuing therefrom toward the body. When a person is using a spray of this character for shampooing the water oftentimes shoots a considerable distance out of its normal path.

I have therefore devised a guard which will eliminate the above disadvantage by confining the water issuing from the device, to the portion being sprayed.

Referring to the drawings in detail, the numeral 5 designates a pipe having a spray head 6, which carries the usual perforated surface 7.

To the head 6, I attach a guard ring 8 as by braces 9, 11, 12 and 13. The guard ring 8 has its lower extremity upon a plane 45 below the plane of the perforated portion 7.

With this construction, when the spray is being employed, the guard ring is placed against the portion being sprayed, as for instance, the head, assuming that a shampooing operation is being performed with the result that the operator washing the head can cause the water issuing from the spray to contact the head and hair and can then allow the water to escape between the ring 55 and the spray head, while with the ordinary spray the water would have no place to escape other than flowing away in an uncontrolled manner.

It will thus be seen that by placing this 60 guard ring on the spray, I have accomplished all the objects above set forth.

It is to be understood that the form of my invention herewith shown and described is to be taken as a preferred example of the 65 same, and that various changes relative to the material, size, shape and arrangement of parts may be resorted to without departing from the spirit of the invention or the scope of the subjoined claim.

Having thus described my invention, I claim:—

In a device of the character described a spray head, brackets secured to said head, a guard ring supported by said head and 75 spaced therefrom in such a manner as to permit a discharge of fluid therefrom, the lower extremity of said guard ring being formed on a plane below the plane of the spray head.

In testimony whereof I affix my signature.

EDNA S. DANIELSON.
